CLAIM

The ornamental design for a toner container, as shown and described.

DESCRIPTION

FIG. 1 is a front, bottom, and left side perspective view of a toner container, showing our new design;

FIG. 2 is a front, top, and right side perspective view thereof;

FIG. 3 is a front, top, and right side perspective view thereof in a use condition;

FIG. 4 is a front, bottom, and right side perspective view thereof in a use condition; and,

FIG. 5 is a bottom plan view thereof in a use condition.

The broken lines in the drawings depict environmental subject matter only and form no part of the claimed design. To the extent that any portion of the toner cartridge is not shown in FIGS. 1-5, such a portion is hereby disclaimed.
